TIN PLATE SORTING APPARATUS

Alfred L. Kronquest, Syracuse, N. Y., assignor to
 Continental Can Company, Inc., New York,
 N. Y., a corporation of New York

Application September 7, 1937, Serial No. 162,823

3 Claims. (Cl. 209—88)

The invention relates generally to sheet or plate feeding means and has for an object to provide novel apparatus for detecting and rejecting sheets or plates of improper thicknesses, thus sorting the units being fed or separating from the units of proper thickness those which are of improper thicknesses.

In can making or similar industries, it is desirable that the tin sheets fed to the various machine unit should be of uniform thickness. When sheets of improper thickness are employed in manufactures of this type they form inferior products or cause breakage of machine parts. The invention resides in the provision of novel sheet gauging means engaged by the tin sheets as they are fed for detecting whether the sheets are of greater than proper thicknesses, and sheet rejecting or sorting means controlled by the gauging means.

Another object of the invention is to provide a novel apparatus of the character stated in which is provided novel means for engaging the fed sheets at both edges and in a manner preventing false actuation of the sheet rejecting devices because of localized faults such as list edges, or edge creases or dents, as distinguished from body thickness.

Another object of the invention is to provide novel means for multiplying the movement of gauge parts effected by actual sheet or plate engagement so as to effect a more certain and positive control of the rejecting or sorting devices.

With the above and other objects in view that will hereinafter appear, the invention further resides in the novel details of construction, combination and arrangement of parts first fully described in the following detailed description, then particularly pointed out in the appended claims, reference being had to the accompanying drawings, in which:

Figure 1 is a somewhat diagrammatic vertical longitudinal section illustrating one form of sheet or plate gauging and sorting apparatus.

Figure 2 is a diagrammatic plan view illustrating the control circuit connections between the sheet gauging and sheet ejecting devices.

Figure 3 is an enlarged detail side elevation of the sheet gauging and ejecting device controlling means.

Figure 4 is a face view of the parts shown in Figure 3.

Figure 5 is a plan view of the parts shown in Figure 3.

Figure 6 is a horizontal section taken on the line 6—6 on Figure 4.

Figure 7 is a vertical longitudinal section illustrating a modified form of sheet or plate gauging device.

Figure 8 is a plan view of the gauging device shown in Figure 7.

Figure 9 is a detail face view of the sheet or plate engaging rollers shown in Figure 7.

In the drawings in which like reference characters indicate like parts in all of the figures, A designates a tin sheet or plate gauging and ejection controlling unit, B an ejecting unit, and C a bed over which the sheets or plates are fed for having operations performed thereon, or for simple sorting purposes.

The unit A comprises a lower support frame 15 head 5 to which the bed plate may be secured, as at 6, and which has a pair of guide grooveways 7 formed therein and arranged vertically in parallel, spaced relation. Each grooveway accommodates a bracket bearing member 8 carrying a tin sheet or plate supporting roller 9 supported on a stud 10. It will be observed by reference to Figures 3 and 5 that these rollers are offset one from the other in the direction of movement of the sheets or plates thereover, or in other words one said roller is positioned in advance of the other.

The brackets 8 are vertically adjustable and are slotted as at 11 to receive securing screws 12. Each bracket also includes a vertically disposed threaded bore 13 in which a micrometer screw 14 operates. The screws are held captive in a bearing plate 15 secured, as at 16, to the head 5, and the plate is provided with indicator marks 17 and the screw head with suitable gauge scale equipment 18. By manipulation of the screws 14 the positions of the rollers 9 in the bed opening 19 can be varied. See Figures 3 and 4.

At a point above the lower head 5 an upper support frame head 20 is mounted. A supporting bracket member 21 is secured as at 22 upon the head 20 and includes a head portion 23 at each side of which a micro switch unit 24 is secured as at 25. These micro switch units are so called because the movable contacts therein move only .002 of an inch in making and breaking contact. Since these switches are well known, and disclosed in detail in the patent to P. K. McGall, 1,960,020, of May 22, 1934, further detailed description thereof is thought to be unnecessary.

The bracket member 21 also includes a foot portion 26 and a pair of laterally projected ears 27. An L-shaped lever 28 is disposed at each side of the bracket member, as shown in Figures

4 and 5 of the drawings, and it will be noted that the base of each L is very short, and the upright very long, so that movement imparted to the base arms will be compounded many times at the upper end of the upright arms. At the juncture of the base and upright arms, each lever carries a roller 29 and each base arm is pivoted at its free end to the foot portion 26 on a horizontally disposed pivot pin 30 as shown in Figures 3, 4, 5 and 6. The pivot pins are offset or staggered as shown in Figure 6 so that each of the rollers 29 is centered over one of the lower rollers 9 previously referred to.

A stop screw 31 is adjustably mounted in each bracket ear 27, and each lever 28 is yieldably held against one of the screws by a spring 32 socketed in the respective lever, and in a receiving socket in a lug 33 formed on the bracket in opposition to said lever. The springs may be adjusted to increase or diminish the energy stored therein by screw plugs 34. At its upper free end each lever 28 carries a spring pressed contact pin 35 engageable with the movable contact actuating pin 36 of the respective micro switch 24.

The sheet or plate ejecting unit B shown in Figure 1 is but one example of means which may be controlled by the gauge and control unit for sorting sheets or plates, or rejecting units of improper thickness. The unit shown includes a frame 37 supported in the bed C, an ejector apron 38 pivoted at 39 on the frame and connected by a crank lever 40 with the core piece of a solenoid 41. The receiving end of the apron 38 normally is above the bed opening 42 and does not interfere with passage of the tin sheets or plates, but whenever the solenoid is energized by operation of the control unit the apron dips into the opening 42 and intercepts the unit of improper thickness and directs it into the receiving chute 43 from whence it is delivered by feed rolls 44 onto a receiving table or conveyor 45.

In Figure 2 of the drawings I have diagrammatically illustrated one manner of electrically connecting the controlling and ejecting units A and B. The micro switches 24 are connected in series, by suitable circuit wiring 48, with a power source 47 and the solenoid 41. With the switches thus connected, the solenoid will not be energized, and the ejector unit B will not be caused to junction unless both switches 24 are closed simultaneously. The purpose of this manner of electrically connecting the switches, and the offsetting or staggering of the gauging rollers 9 and 29, is to assure against the ejection of sheets or plates which are not actually of improper thickness but merely embody localized faults, such as list edges, edge creases, or dents. It will be obvious that by offsetting the rollers, an imperfection encountered and quickly passed over at one edge only of the sheet or plate will actuate one switch only, and this will not suffice to complete the solenoid control circuit as hereinbefore explained. The micro switches 24 are of the normally open or circuit broken type and the series circuit through them can be completed only by pressing inwardly both switch pins 36 simultaneously.

The tin sheets or plates are designated S. It will be obvious that each sheet or plate fed between the roller sets 9 and 29 will separate the opposed rollers to an extent equivalent to the thickness of said sheet or plate. By adjustment of the screws 14 a certain tolerance is determined and every unit of excess thickness 75 will impart sufficient movement to the levers 28

to complete the ejector circuit through the switches 24 and effect an ejection of that unit.

When the apparatus is to be used for sheet or plate sorting, a pile of sheets will be fed through the apparatus and all units of greater than proper thickness will be ejected, leaving only units of the desired thickness or less than the desired thickness in the remaining pile. Then the rollers 9 can be set for a minimum desired thickness control and the pile again run through the apparatus, and the units of desirable thickness would this time be ejected and the remaining pile would then contain only such units as are of less than the desired thickness. By this practice it is a simple matter to accumulate three piles of units, those over the desired thickness, those of the desired thickness, and those under the desired thickness.

In Figures 7, 8 and 9 I have illustrated a modified form of the invention in which a novel means for multiplying gauge roller movement is employed, and in which the ejector unit control means includes a light sensitive circuit. In this form of the invention the machine bed opening 48 accommodates a supporting roller 49 mounted in a fixed bracket 50. The roller 49 is opposed by a movable gauge roller 51 carried in the bifurcated lower end 52 of a plunger 53 which extends upwardly through an aperture in the bottom of a cylinder 54 secured at 55 to a stationary cross frame member 56. The open top of the cylinder is closed by a removable cover 57 which completes a hydraulic chamber 58 in which a large diameter piston member 59 reciprocates, said piston member being secured at 55 upon the upper end of the plunger 53. A spring 60, coiled about the plunger 53 between the cylinder 54 and the bifurcated head 52, serves to yieldably hold the rollers 49 and 51 in engagement.

The cylinder cover 57 has an upward extension 61 equipped with a small bore 62 in which a piston 63 reciprocates. A stem 64 attached to the small piston 63 extends upwardly through an aperture provided therefor in the extension 61 closure or cap 65.

A column of liquid 66 is trapped between the pistons 59 and 63 and serves to transmit the movement of the former to the latter. The large piston has fifty times the displacement of the small piston 63, and consequently, when the large piston moves .001 of an inch, the small piston will be moved .050 of an inch.

A light source 67 is secured as at 68 to the frame member 56, and a light beam is emitted from this source through a narrow slit 69 toward an aligned photo electric or other light sensitive cell 70 likewise supported, as at 71, on the frame member 56. A control lever 72 has its free end normally positioned for obstructing the beam of light as shown in Figures 7 and 8 of the drawings. This lever has its other end bifurcated and secured at 73 to the small piston stem 64 and is pivotally supported intermediate its ends as at 74 upon a bracket 75 carried by the cylinder cover 57. The pivot 74 is so positioned as to provide the lever with long and short end portions so that movement imparted to the short end will be compounded at the long end. The leverage ratio preferably is three to one. By thus proportioning the pistons and the lever, movement of .001 of an inch on the part of the large piston will develop .150 of an inch or approximately $\frac{1}{2}$ of an inch at the light beam obstructing end of the lever.

In Figure 8 of the drawings, I have diagrammatically indicated control circuit connections between the light sensitive unit 70 and the sheet or plate ejector unit solenoid. In this illustration power lines are indicated at 76. Each time a sheet or plate separates the gauge unit rollers a sufficient distance to cause the lever 72 to uncover the light beam slit 69 the relay 77 will be energized by control of the light sensitive unit 70 and the usual auxiliary equipment connected with the relay in the energizing circuit 78 as diagrammatically shown. Whenever the relay 77 is energized it will complete the ejector circuit 79, energize the solenoid 80 and bring about the 15 ejection of the excessive thickness sheet or plate in the manner hereinbefore described.

From the foregoing description, taken in connection with the accompanying drawings, it is thought that the novel details of construction, 20 the manner of use, and the advantages of the invention will be readily apparent to those skilled in the art to which the invention relates.

I claim:

1. In apparatus of the character described, the 25 combination of an electrically actuated sheet ejecting means, a pair of control devices adapted to be moved by opposite edge thickness portions of tin sheets moving therewith, and a pair of normally open control switches one actuatable on 30 each said control device, said switches being connected in series with said ejecting means, and said devices being slightly offset one from the other in the direction of movement of the sheets so that both devices will simultaneously engage 35 even short sheets being fed therewith whereby said ejecting means will be actuated to eject a sheet only upon movement of both said control devices occasioned by abnormal conditions existing at both edges of said sheet.

2. In apparatus of the character described, 40 electrically actuated tin plate movement controlling means, a pair of stationary rollers en-

gageable with opposite edge portions of fed tin plates, a movable roller opposed to each stationary roller and adapted to be moved apart by engagement of improper thickness tin plates, a control switch associated with each movable roller, and a pivoted lever supporting each movable roller and having a portion engageable with the associated switch for actuating the same, the relation of each movable roller, pivot and switch engaging portion being such that the movement 10 of displacement of each movable roller is increased manyfold at the respective switch engaging portion, said switches being normally open and connected in series with said movement controlling means, and said movable rollers being 15 slightly offset one from the other in the direction of movement of the tin plates so that both devices will simultaneously engage even short sheets being fed therewith whereby said ejecting means will be actuated to eject a sheet only 20 upon movement of both said control devices occasioned by abnormal conditions existing at both edges of said sheet.

3. In apparatus of the character described, the 25 combination of sheet ejecting means, supporting means, levers pivoted on the supporting means for individual operation, laterally spaced apart rollers located one at the lower extremity of each lever rearwardly of the pivotal axis of the latter in the direction of movement of the sheet, a control device for said sheet ejecting means mounted on said supporting means inoperative by said levers individually, said levers being operable jointly to actuate said control device, said levers being slightly offset one from the other in the 30 direction of movement of the sheets so that both rollers will simultaneously engage even short sheets being fed therewith whereby said ejecting means will be actuated to eject a sheet only upon 35 operation of both levers occasioned by abnormal 40 conditions existing at both edges of the sheet.

ALFRED L. KRONQUEST.
